UNITED STATES PATENT OFFICE.

CHARLES F. C. HAHN, OF TOLEDO, OHIO, ASSIGNOR OF ONE-HALF TO
JOSEPH SIMON, OF SAME PLACE.

COT-BED.

SPECIFICATION forming part of Letters Patent No. 290,418, dated December 18, 1883.

Application filed June 20, 1883. (No model)

To all whom it may concern:

Be it known that I, CHARLES F. C. HAHN, of Toledo, in the county of Lucas and State of Ohio, have invented certain new and useful 5 Improvements in Cot-Beds; and I do hereby declare the following to be a full, clear, and exact description of the invention, such as will enable others skilled in the art to which it app pertains to make and use the same.

10 My invention relates to an improvement in cot-beds, the object of the same being to provide a bed of this character which shall be adapted to be folded in a compact body without removing any portion thereof, thereby ren dering the accidental loss of any part impos sible. A further object is to provide a bed which shall be simple in construction, of few 15 parts, light in weight, and which can be produced at a small cost; and with these ends in view my invention consists in certain details 20 of construction and combinations of parts, as will be hereinafter fully described, and pointed out in the claims.

In the accompanying drawings, Figure 1 is 25 a view of my improved bed in its open position. Fig. 2 is a view thereof in its closed position. Fig. 3 is a detached view of one of the supporting structures as it appears when folded. Fig. 4 represents the hinge connecting the two 30 sections of the side rail and central supporting structure. Fig. 5 shows the form of hinges connecting the legs to the side rails.

The legs or standards A, the cross-braces B, and the guide-bars C constitute the support ing structures of the bed, and are adapted to be folded in the position shown in Fig. 3 of the drawings by means of the hinges T and U. The lower ends of the legs A are provided with tenons P, adapted to fit into mortises Q, formed 35 in the cross-braces B, the latter being pivot ally secured to the legs at V, and pivotally se cured to each other at W. The upper ends of the legs A are also provided with tenons R, adapted to fit in mortises S, formed in the side 40 rails, F. These legs are also secured to the side rails by the hinges T and U, which also serve to guide the tenons in their respective mortises when being unfolded. The guide-bars C are pivotally secured at one end to the cross- 45 braces B and at the other end to the legs A, and are adapted, when the bed is being un

folded and set in position for use, to guide the tenons P of the legs A into the mortises Q. The side rails, F, are divided into two sections connected by the double hinges E, to which 55 latter are also secured the legs A of the central supporting structure.

D represents metallic brace-rods, secured to the side rails, F, and the lower ends of the cross-braces B, and are adapted to guide the support ing structures in a parallel position with the side rails, F, in the folding of the bed, and also to their upright position, as shown in Fig. 1.

The head and shoulder rest is composed of the standards H' and H'', pivotally connected 65 at their upper ends by the cross-bar H'', and pivotally secured at their lower ends to the side rails, F. A metallic bar, I, is secured to the side rail at K, and is provided at its other end with a hook which engages with a staple 70 or screw-eye secured to or with one of a series of perforations formed in the cross-bar H'', and thus keeps the head-rest in any position.

The canvas or other fabric, G, is preferably 75 fastened to the lower portion of the side rail, F, by double-pointed tacks, and to the upper portion of the said side rails by means of button-tacks and eyelets; the edge of the canvas below the eyelet being re-enforced by a wire or cord to prevent the eyelet from tearing out. 80 This canvas from the point L is inclined to the head-rest, where it is secured by tacks. When the bed is folded, the canvas is unbuttoned from the button-tacks and allowed to rest between the side rails. By inclining the canvas, as 85 above described, an easy and comfortable shoulder and head rest is afforded.

It will now be seen that from the construc tion and arrangement of parts my improved bed is very easily folded and placed in posi tion. By means of the double hinge E the sec tions of the side rails are allowed to be turned and placed parallel with each other, and by means of the hinges T and U the supporting structure is placed parallel with the side rails, 95 the tenons withdrawing from the mortises and allowing the side rails to be drawn closely to gether, the different parts assuming the posi tions as shown in Fig. 2. The hook on rod I is adapted to engage with an eye or staple se cured to the side rail, and thus hold the bed 100 in its closed position.

My invention is exceedingly simple in construction, is of few parts, can be rapidly and easily adjusted, is of light weight, can be manufactured at a small initial cost, and packed 5 in a small compass for shipment.

It will be observed that in folding my improved bed no portion thereof is detached, thus preventing the loss or displacement of any of its parts.

10 It is evident that many slight changes in the construction and relative arrangement of the parts might be resorted to without departing from the spirit of my invention; and hence I would have it understood that I do not limit 15 myself to the exact construction herein shown and described, but consider myself at liberty to make such slight changes and alterations as may fairly be considered to fall within the spirit and scope of my invention.

20 Having fully described my invention, what I claim as new, and desire to secure by Letters Patent, is—

25 1. In a portable cot-bed, the combination, with the side rails and the legs A, hinged to the side rails, and provided with tenons at their

upper ends, that enter mortises in the side rails, of the diagonal braces B, pivoted to each other and to the legs A, guide-bars C, pivoted at one end to braces B and at their opposite ends to legs A, the lower ends of the legs being 30 removably connected to the braces B by tenon-and-mortise joint, substantially as set forth.

2. In a portable folding cot-bed, the combination, with sectional side rails and double 35 hinges connecting the sections of each rail, of legs pivotally secured to the ends of the side rails, cross-braces pivotally secured to the legs, near their upper ends, and provided with mortises which receive tenons on the lower ends of the legs, said braces pivoted to each other at 40 their points of crossing, and guide-bars pivotally secured to the said braces and legs, substantially as set forth.

In testimony whereof I have signed this specification in the presence of two subscr- 45 ing witnesses.

CHARLES F. C. HAHN.
